UNITED STATES PATENT OFFICE.

EUGEN WURMSER, OF STRASSBURG, GERMANY.

APPARATUS FOR CLEANING AND POLISHING BOOTS AND SHOES.

1,020,008.

Specification of Letters Patent. Patented Mar. 12, 1912.

Application filed September 27, 1911. Serial No. 651,622.

To all whom it may concern:

Be it known that I, EUGEN WURMSER, a subject of the Grand Duke of Baden, Germany, residing at Strassburg, in Alsace-Lorraine, Germany, have invented new and useful Improvements in Apparatus for Cleaning and Polishing Boots and Shoes, of which the following is a specification.

My invention relates to an apparatus which serves for removing mud, lubricating or blacking and polishing boots or shoes by mechanical means. For this purpose a number of brushes are arranged upon a shaft of which one brush provided with stiff and hard bristles is combined with a discharge tube through which the dust and dirt can fall into a receptacle. The other brushes serve partly for smearing the blacking, polishing cream or the like over the boots or shoes, and also for polishing them. In order to provide the brushes from time to time with the lubricating material without consuming too large a quantity and in a simple manner, cylindrical containers are provided which are filled with the lubricant. These containers rest upon angle levers, which are pivoted on two axles standing at right angles with respect to each other. By this arrangement it becomes possible on the one hand to place the blacking device quite at the rear wall of the frame and to direct it against the brushes in a simple manner by moving the hand lever, and to press it against the said brushes with any desired firmness of pressure. A roller placed in the receptacle and preferably made of hard wood receives the lubricant from the container and transfers it in thin strips over the brushes so that no lumps are applied to the latter which might be thrown off by reason of the centrifugal force. By this arrangement there is considerable saving in lubricant.

In the drawing: Figure 1 is a front elevation of the device with the roller raised. Fig. 2 is a vertical cross section.

The box *a* can be closed by means of a roller shuttle *b* having handles *c*. In the lower part of the box is a place *d* for the receiving of the dust and dirt and a space *e* for holding the motor. In the upper part of the box are arranged the brushes above

the partition *f*, which brushes are placed upon a shaft *g* rotated by the motor through the pulley *h*. The brush *k* serves to remove dust and dirt from the boot or shoes and is located partially within a tube *l* the shape of which is so chosen that the dirt thrown off passes into this tube and falls down from thence into the space *d*. The brushes *m* and *n* serve for distributing the lubricant over the boots or shoes, the brushes *m* being designed to distribute blacking and the brushes *n* to distribute paste or cream. For the purpose of supplying the lubricant to these brushes there are angle levers *o* *q* which rotate upon the axle *p*. One limb *o* of the lever is formed as a handle, while the limb *q* bears a receptacle *r* which is filled with the lubricant. In the receptacle *r* is rotatably supported a roller *s*, which transfers the lubricant from the vessel to the brush. For this purpose the handle *c* is somewhat raised and the angle lever is then turned about the axle *t* until the receptacle stands behind the brush and can be pressed against it by the aid of the handle *o*. When the brush has been charged with lubricant, the lever is again allowed to fall into the position indicated in Fig. 1. The brush *n* is intended to polish the lubricated boot or shoe and the disk *v* covered with felt, flannel or the like is intended for distributing the shoe cream.

I claim:

85
A shoe polishing apparatus comprising in combination, a rotary brush for applying the dressing or polish to the shoe, a lever mounted to swing about vertical and horizontal axes, a receptacle for the material mounted on said lever and adapted to be shifted thereby into and out of proximity to said brush, and a rotary element mounted in said receptacle to engage the contents thereof and projecting from said receptacle to be engaged with said brush, substantially described.

In testimony whereof I have signed my name to this specification in the presence of two subscribing witnesses.

EUGEN WURMSER.
